[57] ABSTRACT

This invention is directed to tube making apparatus and method including (1) a tube forming and welding unit, (2) a vertical-drum drawing and/or sinking unit, (3) a derodding and cold blooming unit, (4) a horizontal-drum sinking unit, (5) a cleaner and straightener unit and (6) a swager to be used with all the earlier mentioned units.

FIG. 31

APPARATUS AND METHOD FOR MAKING NEEDLE TUBING

BACKGROUND OF THE INVENTION

1. Field of the Invention

The invention relates generally to the forming of tubing from metal strip, welding the formed tube, drawing and sinking the welded tube, cleaning and straightening the drawn-sunk tube, tag-swaging tube ends as needed, inserting and removing mandrels for drawing tubing and the apparatus required for these various steps. Although the disclosure is specifically directed to medical needle tubing, it is obviously applicable to any small tubing between 0.010 and 0.325 final OD used in other arts.

2. Description of the Prior Art

Although the prior art shows the broad steps and apparatus described in the preceding paragraph, each of the steps or units needed redesigning to consistently produce high quality tubing with a minimum of cost, wastage and noise. The drawing and cold blooming units are completely redesigned over the prior art as is the welding and quenching block and the die mounting and movement of the swagers.

SUMMARY OF THE INVENTION

The tube-former welder unit provides a novel alignment of rolls, increased diameter of rolls proceeding downstream to overdraw the tubing and welding and quenching block.

The draw and/or sink unit provides an entirely novel design, including such features as tandem storage drums, movable and tandem die holders, and mandrel insertion and removal to permit continued reuse of mandrels.

The cold blooming unit provides an entirely novel design, including such features as a pulling box and successive blooming rolls positioned at different angles relative to the tubing. The flexible bearings of the pulling rolls permit pulling of the welded tubing through the blooming rolls without splitting the tubing.

The sink unit provides a novel die holder and oiling mechanism and clamping mechanism for tubing ends.

The straightener unit provides a novel pulling box and particularly the belt-gear arrangement for pulling the tubing.

The swager units provide a novel design of a precise mechanism for controlling the backer throw and swager die opening.

BRIEF DESCRIPTION OF THE DRAWINGS

FIG. 1 is a front perspective view of the tube forming and welding unit;

FIG. 2 is a top plan and horizontal section on line 2-2 of FIG. 1;

FIG. 3 is a vertical section on line 3-3 of FIG. 2;

FIG. 4 is a perspective view, partly sectioned of the welding and quenching block;

FIG. 5 is a vertical section on line 5-5 of FIG. 4 through a pincher roll;

FIG. 6 is a perspective view of the vertical tandem tube-drawing unit being used to draw the welded tubing;

FIG. 7 is a perspective view of the vertical tandem tube-drawing unit being used to sink the welded tubing;

FIG. 8 is a partial perspective, partial section, showing the tandem drums and a die holder unit of the vertical tandem tube-drawing unit;

FIG. 9 is a top plan view of the tube gripper mechanism of the tandem drums;

FIG. 10 is a vertical diagrammatic view of the mandrel operation side of the vertical tandem tube-drawing unit;

FIG. 11 is a vertical section on line 11-11 of FIG. 10;

FIG. 12 is an enlarged vertical section showing the mandrel in relation to the puller roll;

FIG. 13 is a partial perspective, partial section view showing a puller box;

FIG. 14 is a perspective view of the cold blooming mill;

FIG. 15 is a vertical section on line 15-15 of FIG. 14;

FIG. 16 is a top plan view of a series of horizontal tube-sinking units and storage coil;

FIG. 17 is a side plan view of the unit of FIG. 16;

FIG. 18 is a vertical section on line 18-18 of FIG. 16;

FIG. 19 is a vertical section of the tube gripper mechanism of the horizontal drums;

FIG. 20 is a partial top plan view showing the starter-driving mechanism of the horizontal drums;

FIG. 21 is a horizontal section of the die holder of the sinking units;

FIG. 22 is a vertical section on line 22-22 of FIG. 21;

FIG. 23 is a detail view of the tube guide leading into the die holder of FIG. 21;

FIG. 24 is a top plan view of the housing holding the rubber rolls;

FIG. 25 is a vertical section on line 25-25 of FIG. 24;

FIG. 26 is a top plan view of a tube cleaner and straightener unit;

FIG. 27 is a vertical section on line 27-27 of FIG. 26;

FIG. 28 is a front plan view with sections broken away of the tube puller box of FIG. 27;

FIG. 29 is a vertical section on line 29-29 of FIG. 28;

FIG. 30 is a partial perspective, partial section view of a swager;

FIG. 31 is an end view showing the swager jaws closed; and

FIG. 32 is an end view showing the swager jaws open.

DESCRIPTION OF THE PREFERRED EMBODIMENTS

A continuous coil of 304 stainless steel strip 11 is mounted on a rotating table 12 so that the vertical strip 13 passes over beveled roll 14 and then rotates 90° to become horizontal before passing through wiping unit 15 having a wet cleaning solvent, adjustable clamping pad station 17 and dry wiping adjustable clamping pad 18. The clamps are adjustable through screws 19. Various metals and their alloys may be used depending on the desired end product. As an example, to produce a 0.125 inch diameter as-welded tube for processing into hypodermic needle tubing, a practical selection of material would be 304 stainless steel strip 0.010 inch

thick, being 0.368 inch in width, which is approximately 80 feet in length per pound.

The horizontal strip 13 then passes to the tube forming unit by first passing over a female adjustable width roll 21 which aligns the strip horizontally through the use of the micrometer head adjustment 22. It next passes under female roll 23, transfers to female roll 24 and runs between female roll 24 and male roll 26. These three rolls are in precise vertical alignment and are adjustable in width to accommodate variances in strip mill tolerances. Furthermore the three rolls serve to steady and center the strip before any forming or breakdown occurs. It then passes to the first breakdown station, including an upper male roll 27 and lower female roll 28. The design of rolls 27 and 28 is such that the strip edges are formed upwardly in a desired arc. The strip then passes through stabilizing guide rolls 31 and to the second breakdown station, including an upper male or tongue roll 32 and a lower female roll 33, the design of which is such that a broad arc is formed on the bottom center of the strip therefore turning the strip edges further upwardly. It then passes through stabilizing guide rolls 34 and to the third breakdown station, including an upper male or tongue roll 36 and a lower female roll 37, the design of which is such that a tightening of the arc previously formed at the bottom and center of the strip occurs so that both strip edges are turned further upwardly. After this, it passes between an upper 38 and lower 39 stabilizing guide roll and then between a first pair of horizontal forming rolls 41, 41 which form the upturned strip edges toward each other. At this point, an internal diameter gas lance 42 enters the now being formed tube, to extend further downstream as the seam opening hereafter will not be sufficient to receive the lance.

The partially formed tube passes between an upper 43 and lower 44 stabilizing guide rolls and then between a second pair of horizontal rolls 46, 46 which form the strip edges into an almost closed tube, leaving an approximate gap or seam of 1/16 inch. The tube then passes through upper 47 and lower 48 stabilizing guide rolls and then to the closing and seam guiding station, including a lower roll 52 and an upper roll 49 which houses a centered replaceable clock spring steel 0.010 inch thick seam blade 51 which serve to further close the tube seam and align and steady the seam to top and center position. The tube then passes to the final closing station and between upper roll 53 and lower roll 54 which abut the open edges of the tubing.

The tube then passes through a bushing 55 into a gas box or welding chamber 56 where it immediately passes through a pair of pincher rolls 57, 57 detailed in FIG. 5 which are horizontally adjustable by knob 40 and vertically adjustable by nut 60. The horizontal adjustable knobs are secured by a locking pin 99. Each pincher roll includes a bearing 58, a lower thrust washer 59 and an upper thrust washer 61. The bearing 58, the lower thrust washer 59 and the upper thrust washer 61 are manufactured from an electrical insulating material (such as nylon) to assure that the pincher rolls 57, 57 are insulated from electrical current. The pincher rolls 57 are mounted on a threaded spindle 101 which is assembled through a brass mounting block 102 and the entire assembly (FIG. 5) is secured by a retaining bolt 100 and locking nuts 103.

Immediately beyond the pincher roll is the welding point 62 which is followed by a carbon brush 63 which

is spring 65 pressured against the bottom of welded tube 64. The carbon brush 63 directs the flow of electrical currents in the most beneficial direction; which is away from the pincher rolls 57, 57 and along the tubing 64 to the brush 63 after which the tube exits from the welding chamber into the water quenching box 66 which the tube traverses to exit through a fitted bushing 67 to remove water from the tube which then passes over drip box 68 to catch any water that may fall from bushing 67. A cover 69 is movably mounted over the quenching box guided by dovetail 104 and controlled by finger recess 80. Through the cover is a water line 71 which terminates in a series of openings 72 which are aligned, when positioned forward, above the tube 64 so that cool running water immediately comes in contact with the entire length of the tube within the quenching box. The cover also prevents water and steam escaping from the quenching box. Water is constantly removed from the box through drain 73.

Prior to this time, there were one or two pairs of pincher rolls similar to pincher rolls 57 downstream of the welding point 62. These additional rolls were brought into use, caused a movement in the molten weld puddle which weakens or destroys the seam weld. Elimination of downstream pincher rolls eliminates working of the molten weld puddle. Furthermore, the introduction of additional pincher rolls requires that the welding chamber 56 be designed larger and therefore require more shielding gas to be used. Additional downstream rolls also require longer travel and time before cooling water can be applied. The tube is welded at about 2,450° F. and the carbide precipitation range is 900° to 1,400° F. for 304 stainless steel and it is recommended that cooling through this range be very rapid. Therefore elimination of downstream pincher rolls shortens the tube travel to less than 5 inches and preferably about 2 inches before cooling water is applied in quenching box 66 as opposed to approximately 6 inches prior to this time, causing the cooling rate to be very rapid through the carbide precipitation range.

The welding and quenching unit is formed and machined from a single cast block 50 with channels 78 circulating water around the welding chamber 56 for cooling purposes and being transferred by flexible tube 123 to cover 69. Channel 78 has a clean-out plug 98. The cast block 50 is adjustable vertically by leveling screws 165 and horizontally by locking bolt 90 which allows complete alignment with the tube path of travel. When the tube first enters the welding chamber 56 the first inch of travel takes it to the end of the pincher rolls 57, 57. After traversing another 1/4 inch, it reaches a welding point 62 and after another 1/4 inch it reaches the brush 63. 3/8 inch beyond the brush the tube passes through a 1/2 wall section and then 2 1/4 inches through the quenching chamber 66 and a final 5/8 inch through bushing 67.

Eddy currents are eliminated or reduced to a minimum by insulating the pincher rolls 57 and providing brush 63 immediately downstream of the welding point and grounding the entire casting at 79. Then brush 63 which is mounted in a brass sleeve 70 is threaded directly in the welding casting 50 and is tensioned by the brush adjusting screw 75 through carbon brush spring 65. Thusly the brush 63 directs current to the work or ground 79.

Above the weld point 62 is movably mounted the torch head of a conventional DC heli-arc welder 74 having a tungsten needle pointed electrode 76 and a shield 77 through which a mixture of helium-argon gas is passed into the welding chamber 56. The same gas is fed inside the formed tube by gas lance 42 which terminates as the tube enters the welding chamber 56. Surrounding the shield 77 is a cover plate 45 which seals the welding chamber 56 but allows the tungsten needle point 76 to be adjusted in all directions while preserving the gas atmosphere in the welding chamber 56. Viewing glasses 179 are provided for observing the tube before and after welding.

The DC current and the high frequency starting currents are furnished by a conventional power source manufactured by Miller Electric of Appleton, Wis., having input characteristics of 230/460 volts, 60 cycle, three phase with an output welding range of 10 to 335 amperes.

When operating, DC current is applied to the electrode 76. To aid in establishing an arc across the air gap to the tube seam, high frequency current is momentarily applied and then released as soon as the arc is established. The controlled flow of current to the tube seam produces a melding of the tube edges which flow together forming an as-welded tube 64.

After passing over drip box 68, the welded tube goes through vertical upper 81 and lower 82 sizing rolls and a pair of horizontal sizing rolls 83, 83 and final vertical upper 84 and lower 86 sizing rolls, after which it is cut into desired lengths, e.g., 10 or 20' after passing onto rack 88. A swager 87 is mounted in the cabinet at the end of the tubing run. The dies in the swager 87 are designed to open the closed cut end of the tube. The dies work the closed end open allowing the tubing opening to be pushed over a mandrel mounted slightly back of the swager dies which completely opens the tube.

The lower driven rolls 24, 28, 33, 37, 52, 54, 82 and 86 have a downstream increased diameter of 0.002 inch for each roll in order to slightly overdraw the tubing and to eliminate a slipping clutch mechanism normally used for this purpose. Roll 24 may be 1.700 inch and roll 86 may be 1.716 inch in diameter, i.e., an increase of slightly more than 1 percent from roll to roll, the range of which could be 0.5 to 2 percent.

On the control panel (FIG. 1), a weld power switch 110 energizes the input power source, switch 111 energizes the DC output, the DC output range is regulated by rheostat 107 and the consumed amperage is viewed on the ammeter 109. The momentary high frequency current is initiated by push button 116 and voltage readings are viewed on voltmeter 105 by closing voltage sampling push button 112. The driving of the tube through the forming and welding stations is by an adjustable speed DC motor 91 which is controlled by switch 113, and can be jogged by switch 114. An adjustable potentiometer 115 adjusts the speed of the DC motor 91, the percentage of which can be viewed on the speed indicator 117. Helium-argon gas mixtures are controlled to the gas chamber 56 by a flow control valve and the amount viewed on a glass tube 108. The same gas mixture injected to the interior of the tube by lance 42 is controlled by a flow control valve and the amount viewed on a glass tube 106.

The tube forming and welding mill is driven by a single motor 91 which is coupled to a common shaft 89, by flexible coupling 118, and is supported by self-

aligning pillow block bearings 119. The shaft 89 drives the gears 95 transmitting motion through toothed belts 92 to gears 95 which transmits motion to worm shaft 93 which drives gears 121, rotating drive shafts 122 that is connected by Delrin chain couplings 96 to roll shafts 97, transmitting rotary motion to the lower vertical forming rolls 24, 28, 33, 37, 52, 54, 82 and 86 supported by roll stand assembly 124, 125, 126 (see FIG. 3). The worm drive shafts 93, the gears 121 and drive shafts 122 are enclosed in oil tight gear boxes 120. The common shaft 89 has a motor speed indicating generator 127 mounted on the end opposite the motor 91. The roll shafts 97 are secured by jam nuts 128 and rotate on flanged plastic bearings 129 and highly finished ground thrust washers 130 as a running surface. The forming roll 28 is held to roll shaft 97 by nut 132 and washers 131 between the roll shaft flanges 133. Vertical alignment of the rolls 27, 28 is accomplished by inserting precision shim washers 147 between the roll shaft flanges 133 and the forming rolls 28.

The upper roll shafts 134 are not driven other than by contact with the strip 13 when it is driven by lower forming roll 28. The roll shaft 134 and the forming roll 27 are secured in the same manner as roll shaft 97 and forming roll 28. Roll shaft 134 is secured in a mandrel 143 which has vertical movement in a slot, milled in the roll stands side plates 125 and aligned by dowels 144. Springs 145 exert an upward pressure on the mandrel 143 when downward pressure is released. Pressure to the mandrel 143 and consequently to forming roll 27 is by adjusting shaft 139 by pin 138, thence the end of the adjusting shaft 139 is fastened by the shaft collar 140 securing it through the platen 141. The spur gears 137 when turned either tighten or loosen screws 136 which are threaded into pressure pads 135. These pressure pads 135 are precisely ground and vertical alignment is maintained by guide pins 142. The spur gears 137 and platen 141 are protected by a cover 146. To facilitate a pulse count a limit switch 148 is mounted in such a manner as to be activated by the flats on roll shaft 97 when rotating.

A cut length of tube 64, for example 0.125 inch outside diameter with a 0.010 inch wall having an inside measure of 0.105 inch has inserted therein a 0.080 inch hardened mandrel wire 201. The mandrel is recessed into tube 64 approximately 2 inches and this end assembly is reduced or tagged in swager 202 for entry through die 224 held by die holder 214.

The reduced tube 64 when inserted through die 224 is clamped by tube gripper 204 which in turn is attached to drum 203. The drum 203 is free to rotate on shaft 232 as long as plunger 211 is not depressed into notch 209. When plunger 211 is depressed into notch 209 and side plate 235 is rotating, drum 203 will rotate and pull the tube 64 through the die 224, causing the tube 64 and its walls to form around the mandrel wire 201 and size to the opening of die 224. The drum 203 will remain pulling as long as pressure is exerted on plunger 211 by side plate 235 and reduction is taking place through die 224. The drum 203 will stop pulling when tube 64 has passed through die 224 thereby eliminating pressure on plunger 211 which immediately disengages from notch 209 as it is pushed upward by spring 248.

After the tube 242 is drawn onto drum 203 the free end of the tube 242 and mandrel wire 201 are placed in notch 246 for further operation. The other end is re-

leased from tube gripper 204 and placed through derodder unit 300 which loosens the tube 242 from mandrel wire 201. Then the mandrel wire 201 is removed by puller 229 as hereinafter described. Further reductions of tube 281 may be performed by additional end reductions through swager 202 with or without a mandrel as desired, and various finished sizes of tubing 282 may be produced on this apparatus.

There being a plurality of drums 203 with drive mechanisms, combined with a plurality of die holders 214, drawing can be performed on one drum 203 while tube 242 is being derodded by unit 300, one drum not interfering with the other. In fact, both drums may be used simultaneously to draw, sink or unload.

Control of draw unit 200 is by on-switch 285 and off-switch 286. The drum speed is controlled by switch 284. This drive unit incorporates controlled acceleration when the motor is started to prevent breaking of the tube 64 when it starts through die 224. Control of puller 229 is by switch 287 and speed is regulated by switch 283.

The drums 203, 203 are arranged on shaft 232 separated by sleeve 240 secured by screw 241. Drums 203, 203 are free to rotate on shaft 232 having bearings 236 and thrust washers 237 for rotating purposes. Shaft 232 is supported by flange bearings 234 which are bolted to side plate 235. Shaft 232 is rotated by sprocket 231 which is secured to shaft 232 by woodruff key 239 through sleeve 238 by pin 233. Drive plates 208, 208 are also secured to sleeve 238 and driven simultaneously with sprocket 231. The drive plates 208, 208 contain a plurality of notches 209 and an access notch 247 will receive plunger 211 when depressed. Plunger 211 is free to move in a slot through drum spoke 252 and guide rails 251. A spring 248 exerts upward pressure on plunger 211. This assembly has a cover plate 249.

Tube 64 enters through entrance bushing 217 and travels between upper oiler roll 218 and lower oiler roll 219 which are bolted to arm 262 by bolts 261 and secured to the wall of die holder 214 by screw 269. The lower oiler roll rotates when tube 264 is pushed or pulled and picks up oil from the chamber 216 depositing oil along tube 64. Brush 221 distributes the oil evenly before entering guide tube 222 which is supported by brackets 263 and secured between the die holder 214 walls by screws 271. Brush 221 is anchored to bracket 263 by bolt 264. Upon leaving guide tube 222 the tube 64 enters carbide die 224 which is secured by screw 267 into die holder 214. An oil drain plug 268 is provided in the base of die holder 214.

The die holder 214 is suspended on hardened ground shafts 213 and 212 being allowed to travel along the face of drums 203, 203 with linear bearings 259 being mounted through die holders 214.

The swaged or reduced end of the tube is placed through carbide die 224 and secured to drum 203 through a linkage starting with shaft 245 securing an arm 244 through hole 272 to drum 203. Arm 244 is secured to the tube gripper by pin 273. The tube gripper 204 secures the tube 242 by turning set screw 206 inwardly. Plate 276 causes the tungsten-carbide gripping jaws 277 to close against tube 242. The opposite gripper jaw is contained in notch 279 and the entire assembly is mounted on a base 280 with a cover plate 274 being secured by screws 278.

The tube having been secured to drum 203 by the tube gripper 204 will be wound or drawn around the drum 203 when side plates 208 are rotating and the plunger 211 has been depressed into notch 209. A side pressure will be exerted against plunger 211 as long as tube 242 is being reduced through die 224 and this side pressure causes plunger 211 to remain in notch 209 continuing to drive drum 203. The instant tube 242 discontinues being drawn the side pressure on plunger 211 will be reduced and spring 248 will push upwardly on plunger 211 removing itself from the notch 209 causing drum 203 to stop rotating.

The tube 242 is not coiled around drum 203 and is held in place by rubber rolls 258 pressing against the drum 203. These rolls are arranged on a shaft 257 supported by bearings 256 which in turn are mounted through a slot 254 in plate 253 and secured by a bolt 255. The tube 242 coiled around drum 203 has its free end placed in notch 246 to prevent whipping.

10 The puller unit 229 which removes the mandrel wire 201 is mounted on the drawing unit 200 on a plate 297 being located between clamps 226 and 227. The puller unit 229 is driven by a motor transmitting rotary motor to shafts 215 running through bearings 205, secured in the wall of puller unit 229. Grooved rolls 228, 228 are vertically opposed and the separating distance is adjustable by adjusting shaft 296 having a pointer 293 to indicate the position. The pointer 293 and the adjusting shaft 296 have a thrust washer 294 and are locked into position by a nut 295.

15 The vertically opposed grooved rolls 228, 228 are locked to shafts 215 by woodruff keys 243 and end plates 270 are secured by screws 288. The grooved rolls 228, 228 which when rotating impart a pull or push to the mandrel wire 201, are machined in such a manner as to allow maximum contact to the mandrel wire 201. Grooved rolls 228, 228 are surrounded by a safety cover 298 to prevent injury. Clamps 226, 227 are employed to hold the loosened tube 281 and the as-welded tube 64 while the mandrel wire 201 is being transferred from one to the other. The clamps 226, 227 are composed of hydraulic cylinders 289 being mounted on plate 297. The cylinder rod 292 extends through plate 297 and clamps 226, 227 are fastened to cylinder rod 292 by nuts 250. Guide rods 290 extend through plate 297 for aligning purposes, guide rods 290 being secured to clamps 226, 227 by nuts 250. Attached to the top of plate 297 is a urethane pad 260 being the size of the clamps 226, 227 which in turn have urethane pads 260 secured to their underside. The urethane pads 260 prevents crushing of loosened tube 281 and as-welded tube 64 and being of a ribbed design, prevents slipping. Damage to the urethane pads 260 is prevented by plate 291 being secured at an angle by screw 265.

20 The derodding unit 300 is shown near drawing unit 200 since it is only after a drawing operation that the derodded unit 300 is used. The tube 242 contains mandrel wire 201 and they are seized tightly together after drawing. This combination is inserted through an entry guide 301 and then between a large pair of hardened ground driven blooming rolls 302, 302 which tend to flatten the tube 242 on a horizontal plane relative to the mandrel wire 201. The tube 242 then passes through an exit guide 305 and then immediately between a horizontal pair of idler rolls 303 which tend to flatten the tube 242 in a vertical plane relative to the

mandrel wire 201. The tube 242 then passes between a second pair of idler rolls 304 which are in a plane 45° from the horizontal or vertical which tends to round the tube 242. Thereafter the tube 242 passes between a third set of idler rolls 306 which are in a 90° opposed position relative to idler rolls 304 which tends to loosen the tube 242 from the mandrel wire 201.

After passing the derodder, tube 281 and mandrel wire 201 are returned to the drawing unit 200 and placed in clamp 226, the mandrel wire 201 being fed between driven rolls 228, 228. When clamp 226 secures tube 281 and mandrel wire 201 is engaged by puller rolls 228, 228, the operator can break free the mandrel wire 201 from inside of tube 281 by flexing the mandrel wire 201 downwardly for about 6 inches. After breaking free the mandrel wire 201, an as-welded tube 64 is secured by clamp 227 and the rolls 228, 228 activated so that the mandrel wire 201 is withdrawn from tube 281 and inserted into as-welded tube 64.

The blooming rolls 302, 302 are mounted on shafts 307 and 340 manufactured from "Faflon," i.e., poly-fluorethylene impregnated with cotton which prevents splitting of the tube 242 and 281 during the blooming operation.

The derodder unit 300 is driven by a motor driven chain 334 which drives sprocket 335 which is locked at shaft 312 by woodruff key 337 secured by screw 338. Spur gears 336, 336 are rotated together since they are locked to shaft 312 by woodruff key 337 and secured by screw 338. The lower shaft 312 is arranged between stationary uprights 342 with the bearings 307 and 340 being made of a compressible material. These stationary uprights 342 are joined to the grooved side plate 344 and secured by bolts 345. Holes 343 and 346 are provided for uses other than derodding.

The shafts 312, 312 are secured in position by nuts 341 holding thrust washers 399 and flanged bearings 340 against a shoulder on shafts 312. The upper shaft 312 is mounted between two movable uprights 347 joined by a saddle 349 that is secured by bolts 348. These units are suspended on adjusting shaft 357 and allowed to move vertically in the grooved side plate 344. The adjusting shaft 357 is threaded into the saddle 349 and secured by nuts 356 between platen 351, thrust bearings 359 and thrust washer 358. An indicating pointer 355 is contained by nut 356.

The platen 351 is secured to groove side plates 344, 344 having a screw 353 exerting pressure on rod 354 which restricts movement of adjusting shaft 357.

This basic wire or tube pulling unit is used on derodder unit 300, on the straightener unit 500 as puller 520 and on the drawn unit 200 as puller 229.

When the drive unit is used for the derodder unit 300 hardend and ground blooming rolls 302 are placed on shaft 312 locked by woodruff key 311 and plate 314 secured by screw 315. A stand 308 is secured to a bench top through slots 327 and screw 328. A support 309 contains an entry guide 301 that centers the tube 242 between blooming rolls 302, 302. The support is held to stand 308 by bolts 310. An exit guide 305 receives the tube 242. This exit guide is mounted on upper platen 321 and secured by screws 317.

The first set of horizontal idler rolls 303, 303 are secured respectively to plate 326 and to upper platen 321. The upper platen 321 has a slot 319 as has the plate 326 which allows adjustment through adjusting screws 323 and 324. The upper platen 321 and the

plate 326 are joined to the base 325 by bolts 318. The base is then fastened to stand 308 by screw 329. The idler rolls 303, 303 are fastened to platen 321 and plate 326 by screw 316. Idler rolls 304, 304, 306 and 306 are similarly fastened to platens 321 and plate 326 with adjustments by adjusting screws 323 and 324, the only difference being the angle at which idler rolls 304, 304, 306 and 306 are set.

After the desired number of draw and sink passes have been performed on unit 200 (normally to about 0.060 inch), the tube 282 is taken to the horizontal drum sinking unit 400. There is generally a series of these, providing for several sink passes through different die sizes as desired, with a movable coiling unit 401 removing the tube 282 from whatever drum 412 that constitutes the final sink.

After reducing the tube 282 end at swager 202, it is placed over a roller guide 402 which is secured in end plate 429 by shoulder screw 425 and under a vee-grooved nylon screw 428 which is mounted in end plate 429. The tube 282 is fed through removable die 404 mounted in movable die holder 403. A cover 407 has openings 408 aligned over tube 282 for oil 441 raised by pump 442 through hose 409 to channel 430 exiting through openings 408 unto the tube 282. The oil 441 then returns to reservoir 411 through tube 431. The hose 409 is flexible and longer than necessary to allow for movement and coiling in reservoir 411. The die holder 403 is attached to the cylinder rod 432 and the cylinder 435 is anchored to cabinet 413 through spacing blocks 433 and these units are held by screws 434. The cylinder 435 receives fluid power through tubes 436, 437 and the travel of cylinder rod 432 is controlled by shaft collar 439 which is secured to tube 431 by screw 438 activating limit switch 440. The cylinder 435 is generally powered by a hydraulic pump and the limit switch 440 generally operating a solenoid valve which controls the movement of cylinder rod 432.

A pair of horizontal drums 412, 412 are mounted on each cabinet unit 413 which are driven by motor 415 through gear box 414 transferring power to driving gear shaft 454 which has gear 416 locked to it by key way 455 secured by screw 456.

This driving gear shaft 454 is secured between cabinet 413 and plate 451 by bearing 458 and thrust bearing 450. Motion from gear 416 is transferred to gears 417, 417 which are locked to gear shaft 453 by screw 456. These gear shafts 453, 453 are secured between cabinet unit 413 and plate 451 by bearing 452, 452 and bearing 457, 457. The gear shaft 453 rotates the drive plate 422 while supporting drum 412 on thrust bearing 459 and bearing 462 in such a manner that drum 412 is independent of drive plate 422. Shaft 453 is joined to drive plate by notch 465 and pin 466, having open notches 467 on the outside edges. A cover plate 471 is secured to the top of drum 412 by screw 461 having a starter pin 423 inserted through its thickness and on through the spoke of drum 412. Ring 463 and spring 464 hold starter pin 423 in an upward position. When starter pin 423 is depressed so that it enters notch 467 and drive plate 422 is rotating, drum 412 will rotate similarly. Also mounted on drum cover 471 on the outer edges is a tube gripper 472 which consists of a lower disc 418 and when necessary a shim 468, and upper disc 419 containing notch 421. This assembly is joined to cover plate 471 by screw 449.

60

When tube 282 is passed through die 404 the reduced end is placed between discs 418 and 419 and up through notch 421. Then when starter pin 423 is depressed into driver plate notch 467, drum 412 will rotate wedging or gripping the tube 282 between discs 418 and 419. Continuing pull will hold side pressure on starter pin 423 keeping it engaged in notch 467 of drive plate 422. When the tube 282 has passed through die 404 the side pressure on starter pin 423 will be relieved and spring 464 will push the starter pin 423 upward removing it from notch 467 of driver plate 422 and drum 412 will cease to rotate. Further rotation of drum 412 is damped by rubber rollers 424 which are contained on a shaft 448 having bearings 445 in housing 443. Springs 444 pocketed in housing urge the rubber rollers 424 forward and against drum 412. The housing 443 is mounted to cabinet unit 413 by screws 447 through slots 446 which allows an adjustment of pressure to drum 412. The rubber rolls 424 also contain and control tube 282 when it is coiled around drum 412.

After tube 282 has been through the necessary number of dies 404 and has been reduced to the necessary gage size it is removed from drum 412 and wound onto reel 473 by coiling unit 401. The reel 473 is rotated by driving shaft 474 which is driven by motor in coiling unit 401. An idler shaft 469 allows for positioning a reel 473 of tube 282 on shaft 469 and re-reeling onto shaft 474 and reel 473 for wiping purposes. The tube 282 now having reached the desired gage size is coiled onto reel 473 and is ready for cleaning and straightening on tube straightener 500.

For straightening and cleaning purposes the tube 282 which is coiled on reel 473 is placed on shaft 501 of the tube straightener unit 500. Shaft 501 suspends reel 473 in a tank 502, which contains a cleaning solvent 524. The tube 282 is then placed through clamp 503 which contains wiping pads 510 for further cleaning. A controllable pressure is exerted on clamp 503 by cylinder 508. The tube 282 enters rotary frame 509 which rotates on bearings 526 contained in housing 504. The rotary frame 509 has four centering pegs 511 and one off-set peg 512 which are adjustable and locked by nuts 513. Pads 514 are made from various materials, but mainly cloth such as linen and protect the surfaces of tube 282 as it is passed over and through pegs 511, 512. The rotary frame 509 is driven by timing belt 507 from a variable speed motor located in tube straightener 500.

Tube 282 when leaving rotary frame 509 passes through nylon bushing 533 that centers and protects tube 282, which then passes between timing belts 517 of puller unit 520. These timing belts 517 are driven by driver gears 516 through shaft 312 which is powered by a variable speed motor. The timing belts 517 are maintained in a flat plane by idler gears 518 which are secured to mounting bar 534 having two flange bearings 522 and two thrust washers 521 being secured by nut 523. Tension may be adjusted to timing belt 517 through adjusting screws 519. Further adjustments may be made to position timing belts 517 by moving plate 347 which is illustrated in FIG. 13. After passing through the puller unit 520 the tube 282 passes into and through cutter 515 which cuts the tube 282 into desired lengths.

To further describe the principle of tube straightener 500, the tube 282 is pulled through rotary frame 509 which is rotating normally between 4,000 and 8,000 rpm. The work produced on tube 282 through the off-

set created by offset peg 512 combined with the speed of rotation and rate of linear travel will cause the tube 282 to exceed the yield point of the material from which tube 282 has been processed, which allows it to be dimensioned 360° around the tube 282, causing it to be straightened.

As an example of growth, to start with 304 stainless steel, 0.010" × 0.368", 144" of $\frac{1}{8}$ " OD tubing is welded, there being only about $\frac{3}{8}$ " per foot growth through the welding stage. If the $\frac{1}{8}$ inch tubing is drawn through an 0.093 inch carbide die over a 0.080 inch mandrel, the length increases to 312 inches. If that is then sunk through an 0.083 inch carbide die, the length increases to 344 inches and a further sink through 0.0625 inch carbide die increases the tube length to 461 inches.

It is normal to change from carbide dies (244) to diamond dies (404) at about 0.060 inch diameter. Thus to now sink the tube through an 0.056 inch diamond die yields 495 inches of 17 gage hypodermic needle tubing. Further sinking through an 0.048 inch die yields 584 inches of 18 gage tubing; through 0.041 inch die yields 771 inches of 19 gage; through 0.035 inch die 911 inches of 20 gage; through 0.032 inch die yields of 1,000 inches 21 gage; through 0.028 inch die yields 1,181 inches of 22 gage; and through 0.025 inch die yields 1,348 inches of 23 gage.

These figures are of course approximate and depend on various factors known to the art.

The components which make up the swager unit 600 are in a housing 601 which is generally of a cast material. A hole 621 is bored to receive spindle 607 and flange bearings 602. A bore is also machined in the face 620 to form a recess 623, for inserting a pressed hardened wear ring 609 to avoid wear otherwise of the recess. Freely mounted inside of ring 609 and embedded in hard grease in a roll cage 608 which contains hardened rolls 610 diametrically opposed to one another. The roll cage 608 is designed so that an arc of hardened rolls 610 project beyond the cage both outwardly to maintain contact with the hardened ring 609 and inwardly. The spindle head 622 is directly inside of hardened rolls 610 and has a machined slot 624 centered across its face. This slot 624 contains the backers 612, which have a hardened dowel 611 inserted in the end to prevent wearing, shims 617 and working dies 614, defining a die opening area 625.

The spindle head 622 has a circular precise spindle groove 618 cut in the face. The spindle groove receives backer throw adjusting ring 613 that passes through backer groove 619, which are machined to a precise desired dimension. The spindle head 622 and spindle shaft 607 are made from a single piece and secured in housing 601 by nuts 604 threaded to shaft 607 exerting pressure against thrust washer 603. A pulley 606 is locked to shaft 607 by keyway 605 and anchored in a conventional manner. A spindle cover plate 615 is secured by screws 626 and a roll cage cover plate 616 is secured by screws 627.

The swager unit 600 operates when the spindle 607 and spindle head 622 are revolved by providing rotary motion to pulley 606, the desired speed of which will be determined by the size of the swager 600 and the use of the unit. When the spindle 607 revolves it throws the backers 612 and the dies 614 outwardly by centrifugal force and as the spindle 607 continues to revolve backers 612 pass over hardened rolls 610, driving backers

612 and dies 614 inwardly, thereby causing a hammering or swaging operation to be performed on any material that is placed between dies 614, 614 in die opening 625. The material is generally a tube or shaft which is to be shaped or reduced. The inward movement is produced by backer 612 with its hardened dowel 611 passing between an opposed pair of hardened rolls 610, 610 driven by a rotary motion. This movement can be increased or decreased by removing or adding shims 617. The outward throw of the backers 612 and the dies 614 is by centrifugal force when the shaft 607 is revolved. The amount of throw, i.e. the amount the dies 614 open, must be precise to perform properly, e.g., centering the work and presenting the work from falling between non-working parts of the dies 614, 614.

To control the outward throw of the backer 612, a precise spindle groove 618 has been machined into spindle head 622 to freely receive backer throw adjusting ring 613. The outside diameter of the backer throw adjusting ring 613 is a slip fit into the outside diameter of the spindle groove 618 and the backer groove 619 has an inside radius on the groove equal to the inside radius of the spindle groove 618. The outside radius of the backer groove 619 is more than the outside radius of spindle groove 618, and must be at least enough to prevent the outside radius of backer groove 619 from striking backer throw adjusting ring 613. Therefore, the amount of outward throw of the backers 612, 612 is controlled by the inside diameter of backer throw adjusting ring 613 (see FIG. 32), whereas the inward throw is determined by dowels 611 contacting rollers 610 (see FIG. 31).

The adjusting ring 613, dies 614, backers 612 and/or shims 617 may be readily replaced with different size elements to change the effective working of the swager. Otherwise the swager is useable at any of the stations shown herein. The adjusting ring variance has been shown on its internal diameter but this could be reversed, i.e., a slip fit on its interior with the machined groove on its exterior if other elements were changed accordingly. It is of course the thickness of the adjusting ring relative to the backer grooves that defines the limits of travel of the backers and thus the dies. The precise length of backers 612 is preferably preserved by replacing hardened dowels 611 when wear occurs.

I claim:

1. A process for making metal tubing continuously from a metal strip comprising forming said strip to a tube by passing through an aligned series of mating tongue and groove, idler and driven, rolls of different shapes, passing said tube into an inert gas chamber between a pair of horizontal pincher rolls positioned within said gas chamber, said pincher rolls being electrically insulated from said chamber, welding said tube downstream of said pincher rolls, electrically grounding said tubing downstream from said welding, quenching said tubing downstream from said grounding through the precipitation range prior to any further metal working beyond said pincher rolls, cutting said tubing into desirable working lengths, opening one end of said cut tubing with a swager, inserting a mandrel into said cut tubing through said open end, swaging one end of said mandrel to said tubing, drawing said tubing through a die onto a vertical drum to reduce the inside diameter of said mandrel and wall thickness and outside diameter to desired dimensions, pulling said drawn tube through a plurality of roll pairs by driving at least

one of said pairs, the plane of each pair being at a different angle to bloom said drawn tubing from said mandrel, withdrawing said mandrel from said bloomed tubing, inserting said mandrel in a subsequent length of cut tubing, swaging one end of said bloomed tubing, sinking said bloomed tubing through a die onto a horizontal drum to reduce the inside and outside diameter to second desired dimensions, and passing said sunk tubing through a rotary frame having an offset peg and a plurality of centering pegs.

2. A process for making as-welded metal tubing continuously from a metal strip including forming said strip to a tube by passing through an aligned series of mating tongue and groove, idler and driven, rolls of different

15 shapes, passing said formed tube into an inert gas chamber between a pair of horizontal pincher rolls positioned within said gas chamber, and welding said formed tube downstream of said pincher rolls wherein the improvement comprises quenching said welded tube downstream of said welding point prior to any further working.

3. The process of claim 2 wherein the distance between said welding strip and beginning of quenching is less than 5 inches.

4. The process of claim 2 wherein the distance between said welding step and beginning of quenching is about 2 inches.

5. The process of claim 2 wherein said metal is 304 stainless steel and the quenching is through precipitation range thereof.

6. The process of claim 2 wherein said pincher rolls are electrically insulated from said chamber and said welded tube is passed over an electrically grounded brush between said welding and quenching steps.

7. The process of claim 2 wherein said driven rolls are of progressively increased diameter in the downstream direction to overdraw said tubing.

8. The process of claim 7 wherein said increased diameter is about two-thousandths of an inch at each succeeding driven roll.

9. The process of claim 2 wherein the distance between said welding step and beginning of quenching is less than 5 inches, said pincher rolls are electrically insulated from said chamber, said welded tube is passed over an electrically grounded brush between said welding and quenching steps, and said series of rolls are of progressively increased diameter in the downstream direction to overdraw said tubing.

10. Apparatus for making metal tubing continuously from a metal strip, said strip and thereafter said tubing forming a longitudinal working axis, comprising a series of mating, idler and driven, tongue and groove, forming rolls of different shapes that in successive steps turn said strip into tubing with abutting edges, means for simultaneously driving said driven rolls, means following said forming rolls for welding said abutting edges, means for quenching said welded tubing, means for cutting said quenched tubing into desirable working lengths, a first swager with a die adapted to open a closed end of said cut tubing, means for inserting a mandrel within said open tubing, a second swager with a die adapted to swage said mandrel to said tubing, a (pair of) storage pulling drum(s) mounted vertically (in tandem) on a first horizontal axis, a (plurality of) die mounting carrier(s) mounted (in tandem) on a second axis parallel and coextensive to said first axis (, one of said) having a fourth die(s) adapted to pass said

swaged tubing and mandrel, (any of) said drum(s) adapted to draw said swaged tubing and mandrel through said (one) fourth die and store thereon whereby the internal diameter is reduced to said mandrel and the wall thickness and outside diameter are reduced to desired dimensions, a plurality of mating blooming rolls in pairs in spaced alignment along said tubing axis, the plane of each pair being at a different angle, each blooming roll spaced from its associated mate a sufficient distance to bloom said tubing from said mandrel, at least one of said pairs being driven, a mated pair of pulling rolls in alignment along said tubing axis and downstream from said blooming rolls adapted to pull said mandrel from said bloomed tubing and reinsert same into subsequent length of cut tubing, a third swager with a die adapted to swage said drawn tube end, a (second fifth die removably mounted along said tubing axis, a horizontally mounted drum adapted to sink said tubing through said (second) fifth die and onto said drum to reduce the outside and inside diameter to further desired dimensions, a rotary frame having an offset peg positioned immediate a plurality of centering pegs, said pegs positioned along said tubing axis downstream of said horizontal drum, and means to pull said tubing downstream of said rotary frame.

11. Apparatus for making as-welded metal tubing continuously from a metal strip, said strip and thereafter said tubing forming a longitudinal working axis, including a series of mated, idler and driven, tongue and groove forming rolls of different shapes positioned along said axis that in successive stages turn said strip into tubing with abutting edges, a welding chamber surrounding said axis downstream of said forming rolls, a pair of pincher rolls positioned along said axis in said welding chamber, a welder movably mounted to weld said formed tubing at a point in said welding chamber immediately downstream from said pincher rollers, a series of mated, idler and driven, sizing rolls positioned along said axis downstream of said welding point, and

means for driving one of each mated rolls wherein the improvement comprises a quenching chamber surrounding said axis between said welding point and said sizing rolls with no welded tube working elements before quenching.

12. The apparatus of claim 11 wherein the distance between said welding point and said quenching chamber is less than 5 inches.

13. The apparatus of claim 11 wherein the distance between said welding point and said quenching chamber is about 2 inches.

14. The apparatus of claim 11 wherein said quenching chamber includes a cover movable from open to closed position and provided with bottom openings adapted to be connected to a water supply, said openings being aligned directly above said axis when said cover is in said closed position.

15. The apparatus of claim 11 wherein said pincher rolls are electrically insulated from said welding chamber, and an electrically grounded brush adapted to contact said welded tubing is positioned along said axis between said welding point and said quenching chamber.

16. The apparatus of claim 11 wherein said driven rolls are of progressively increased diameter in the downstream direction.

17. The apparatus of claim 16 wherein said increased diameter is about two-thousandths of an inch at each succeeding roll.

18. The apparatus of claim 11 wherein the distance between said welding point and said quenching chamber is less than five inches, said pincher rolls are electrically insulated from said welding chamber, an electrically grounded brush adapted to contact said tubing is positioned along said axis between said welding point and said quenching chamber, and said driven rolls are of progressively increased diameter in the downstream direction.
